UNITED STATES PATENT OFFICE

90,549

DESIGN FOR A SHOE RACK OR SIMILAR
ARTICLEHarold R. Perry, Swarthmore, Pa., and Chester
S. Jennings, Syracuse, N. Y.

Application June 8, 1933. Serial No. 48,346

Term of patent 14 years

To all whom it may concern:

Be it known that we, HAROLD R. PERRY and CHESTER S. JENNINGS, citizens of the United States of America, residing at Swarthmore, in the county of Delaware and Commonwealth of Pennsylvania, and Syracuse, in the county of Onondaga and State of New York, respectively, have jointly invented a new, original, and ornamental Design for a Shoe Rack or Similar Article, of which the following is a specification, reference being had to the accompanying drawing forming a part thereof.

The figure is a perspective view of a shoe rack showing our new design.

We claim:

The ornamental design for a shoe rack or similar article substantially as shown.

Signed by HAROLD R. PERRY, at Syracuse, in the county of Onondaga and State of New York, this 6th day of June, 1933.

HAROLD R. PERRY.

Signed by CHESTER S. JENNINGS, at Syracuse, in the county of Onondaga and State of New York, this 6th day of June, 1933.

CHESTER S. JENNINGS.
